(57) **CLAIM**

The ornamental design for a bracket as shown and described.

DESCRIPTION

FIG. 1 is a front perspective view of a bracket showing our new design.

FIG. 2 is a rear perspective view of the bracket shown in FIG. 1.

FIG. 3 is a right elevational view of the bracket shown in FIG. 1.

FIG. 4 is a left elevational view of the bracket shown in FIG. 1.

FIG. 5 is a front elevational view of the bracket shown in FIG. 1.

FIG. 6 is a rear elevational view of the bracket shown in FIG. 1.

FIG. 7 is a top plan view of the bracket shown in FIG. 1, shown in a larger scale; and,

FIG. 8 is a bottom plan view of the bracket shown in FIG. 1, shown in a larger scale.

The broken lines in the drawings are included for the purpose of illustrating portions of bracket and form no part of the claimed design.

1 Claim, 8 Drawing Sheets
